UNITED STATES PATENT OFFICE.

ARTHUR LEVIN, OF WINNIPEG, MANITOBA, CANADA.

WINDOW-BLIND ATTACHMENT.

1,251,899.

Specification of Letters Patent.

Patented Jan. 1, 1918.

Application filed March 1, 1917. Serial No. 151,780.

To all whom it may concern:

Be it known that I, ARTHUR LEVIN, of the city of Winnipeg, in the Province of Manitoba, Canada, have invented certain new and useful Improvements in Window-Blind Attachments, of which the following is the specification.

The invention relates to a window blind attachment and the object of the invention is to provide a device which will permit of a blind being bodily moved or adjusted up or down in respect to the window and operated in the usual way when brought to the adjusted position, such arrangement allowing one to exclude light or view through any part of the window while allowing of the admission of light or of a view through the remaining part or parts of the window.

With the above objects in view the invention consists essentially in a pair of guides secured to the window frame at the sides, adjustable telescoping tubes extending between the guides, wheels at the ends of the tubes and operating in the guides, travelers slidably mounted in the guides and provided with extending blind holders and means for adjusting the wheels in vertical position in respect to the guides, the parts being arranged and constructed as herein-after more particularly described and later pointed out in the appended claims, reference being had to the accompanying drawing in which:—

Figure 1 represents an interior view of a window supplied with my invention.

Fig. 2 represents a horizontal sectional view through the window and attachment.

Fig. 3 represents an enlarged detailed horizontal sectional view through a guide and adjoining parts.

Fig. 4 represents a perspective view of one of the travelers.

Fig. 5 represents a fragmentary view of a portion of one of the plates on the guides.

Fig. 6 represents a side view of one of the wheels.

In the drawing like characters of reference indicate corresponding parts in the several figures.

1 and 2 represent the usual uprights or side members of a window frame, 3 the upper cross member and 4 the sill.

5 represents the window which as usual comprises top and bottom sashes.

Ordinarily the view or light is regulated by a window blind mounted on the window

frame at the top, the blind being pulled down a greater or less distance as wished. With this arrangement, if one draws the blind to exclude light or vision through the lower part of the window he necessarily excludes light or view through the top part of the window.

With my construction it is possible for one to have the lower part of the window closed by the blind and the upper part open to allow of the entrance of light or vision through the window. This is a very important feature as will be readily appreciated.

Further one can adjust the blind in the central portion of the window while having the upper part and the lower part open.

I will now describe my appliance:—

6 and 7 represent a pair of upright guides 75 permanently secured such as by nailing to the sides of the window frame. These guides, in the present instance, are of channel iron construction thereby providing in each a pair of spaced runways 8 and 9. The 80 runway 9 of each guide is fitted with a permanent vertically disposed carrier plate 10, which is perforated throughout its length to provide spaced openings 11, the said plates actually forming racks. In this 85 connection, I wish it to be understood that I do not wish to be limited to the precise formation of these carrier plates as they could be readily modified while embodying the rack idea without in the least departing 90 from the spirit of my invention.

Between the guides and crossing the window I locate an adjustable spacing member 12 formed from a tube 13 telescoping within a second tube 14, there being a jam screw 95 15 supplied to allow of the adjustment of the tubes in length. The outer ends of the tubes are each plugged with a short extending spindle 16 which is permanently fastened to the tube by a cross pin 17. When properly 100 adjusted these spindles extend within the guides.

A toothed wheel 18 is permanently secured such as by a pin 18' to each of the spindles, being spaced a short distance and 105 as best shown in Fig. 3 from the end of the tube. The wheels are arranged to operate on the racks with the teeth rolling in the openings 11. Here it is to be noticed that the outer edges of the wheels are clear of the carrier plate 8 (see Fig. 3). On each spindle, between the end of the tube and the

wheel, I mount a traveler 19, which traveler has the opposite sides thereof 20 and 21 parallel and adapted to contact with the inner faces of the plates 8 and 10, these 5 plates actually forming slides for the travelers.

Owing to this arrangement it will be seen that when the member 12 is raised and lowered the traveler plates will have to move 10 up and down in the guides, and that they are allowed no tilting action. Each traveler is supplied with an extending holder 22, one of the holders being provided with a centrally located opening 23, while the other is 15 supplied with a vertical slot 24, the opening and slot being provided to receive the extending ends of the customary spring roller blind, indicated generally by the reference numeral 25.

20 At the one side of the frame I locate an adjusting rod 26 which has the upper end thereof passing upwardly within the guide 7 and mounted on the adjacent spindle 16 between the wheel and the traveler. The body 25 of the rod is carried within a fastener 27 mounted on the frame. This fastener can be of any of the well known constructions, spring lock, jam screw or otherwise, which will allow of the quick releasing and fastening 30 of the rod in any adjusted position.

When one wishes to use this appliance he simply releases the fastener 27 and forces the rod up or down, as wished. As the rod moves it forces the spindle 16, on which it is mounted, with it and in the same direction and accordingly causes the wheels to move up and down on the carrier plates. Owing to the teeth and the openings, the wheels always run evenly and true, that is to say, one 40 side of the appliance cannot get ahead of the other. According to the position of the wheels, so the position of the travelers and consequently the adjustment bodily given the blind. Once the appliance has been adjusted, one can manipulate the blind in the usual way, drawing it partially or fully down, as the occasion may require.

In Fig. 1 the attachment has been shown as adjusted in a position partially down from 50 the top of the frame and the blind has been shown as partially pulled down. In this position light can enter the room at both the top and bottom of the window. Obviously, if one drew the blind fully down, light would 55 be excluded at the bottom of the window,

while the room would be amply lighted with the light coming from the top.

The member 12 is made adjustable so that the appliance can accommodate various widths of windows.

60

In connection with the guides, I wish it to be noticed that they could be placed on the opposing faces of the member 1 and 2 instead of on the inner faces where they are shown. To secure them on the opposing 65 faces of the frame it is only necessary to fasten the back A of the guide to the frame instead of the plate 9 as shown.

What I claim as my invention is:—

1. The combination with a window frame, 70 upright opposing channel-iron guides secured to the frame and a vertically disposed rack associated with one of the flanges of each guide, of a cross member extending between the guides and presenting end spindles reduced in diameter in respect to the body of the cross member, thereby forming shoulders, a pinion permanently secured to each spindle and operating on the adjacent rack and a traveler mounted freely on each 75 spindle between the pinion and the shoulder and with the sides thereof making sliding contact with the flanges of the guides and fitted with outstanding horizontally disposed blind holders.

85

2. The combination with a window frame, 90 upright opposing channel iron guides secured to the frame and a vertically disposed rack associated with one of the flanges of each guide, of a tube extending between the 95 guides, end spindles permanently secured within the ends of the tubes and extending between the flanges of the guides, a pinion permanently secured to each spindle and operating on the adjacent rack and a traveler 100 mounted freely on each spindle between the pinion and the end of the tube and slidably received between the flanges of the guides and provided with a substantially L-shaped horizontally disposed extension forming a blind holder and with the neck of the extension riding the inner face of the adjoining guide flange.

95

Signed at Winnipeg, this 29th day of November 1916.

ARTHUR LEVIN.
